UNITED STATES PATENT OFFICE.

JOHN S. ANDREWS, OF NEW YORK, N. Y., AND JAMES S. ROGERS, OF ROCKPORT, MASSACHUSETTS.

FURNACE GAS-BURNER.

SPECIFICATION forming part of Letters Patent No. 392,175, dated November 6, 1888.

Application filed May 25, 1887. Serial No. 239,372. (No model.)

To all whom it may concern:

Be it known that we, JOHN S. ANDREWS and JAMES S. ROGERS, citizens of the United States, residing, respectively, at New York and Rockport, in the counties of New York and Essex and States of New York and Massachusetts, have invented certain new and useful Improvements in Furnace Gas-Burners; and we do hereby declare the following to be a full, clear, and exact description of the invention, such as will enable others skilled in the art to which it appertains to make and use the same.

Our invention relates to a burner and its adjuncts to be employed in a furnace where gas is used as a fuel, and particularly in a furnace and with an apparatus of the character disclosed in Letters Patent No. 345,649, dated July 13, 1886, for the manufacture and utilization of gas for heating and other purposes; and it consists in the construction, arrangement, and combination of parts, which will be more fully hereinafter described, and pointed out in the claims.

One object of our invention is to produce a burner wherewith the gas employed as a fuel may at the point and instant of combustion be commingled with air, both the gas and the air being at the time of such commingling in a highly-heated state.

A further object is to produce by the commingling of the gas and air in a highly-heated state at the point and instant of combustion a more perfect combustion of the gas than has hitherto been attained.

We are aware that attempts have been made to secure the same results, but, so far as we know, with only partial success.

We attain these objects above mentioned by the apparatus illustrated in the accompanying drawings, wherein the same letters of reference indicate the same parts, and in which—

Figure 1 represents a horizontal sectional view of the bench or walls of a furnace, showing a flue or duct within the walls, but near the inner surface, for conducting the air to the air-chamber formed in the burner. Fig. 2 is a longitudinal vertical section of the furnace, showing the burner, the air-flues in the walls of the furnace, and the apparatus in part for manufacturing gas. Fig. 3 is a transverse sec-

tion of the burner, showing the outer and inner pipes, the exit-tubes for the gas, and the supports for the inner pipe. Fig. 4 is a longitudinal section of the same on the dotted line *x x*, Fig. 3. Fig. 5 is a transverse section of a modified form of the burner. Fig. 6 is a longitudinal section of the same on the line *x x*, Fig. 5.

In the drawings, A indicates a heating chamber or furnace, which is to be presumed as provided with the usual grate and other belongings. In the walls of this chamber or furnace we form an air-duct, B, which communicates with the outer atmosphere at any suitable point, the said air-duct surrounding the entire furnace within the walls of the same. Attached to and communicating with the air-duct B is the burner C, the peculiar construction thereof being more clearly shown in Figs. 3 and 4 of the drawings. This burner consists of an exterior pipe, *c*, and a smaller interior pipe, *c'*, the two pipes being cast integrally or rigidly connected together by suitable studs or arms, and the interior pipe is so arranged within the exterior pipe as to leave but a small space between the tops of the pipes, and so as to form a much larger air-space between the lower sides of the pipes. The upper sides of the pipes are provided with slots *c*³ in the exterior pipe and *c'* in the interior pipe, the said slots being preferably arranged in a zigzag or staggering manner, so as to weaken the tops of the pipes as little as possible, and the slots are connected by means of short pipes *c*⁵, having perforations *c*⁶ in their sides, forming communications between the air-chamber in the exterior pipe and the short pipes *c*⁵.

By having the short perforated pipes forming exits for the gas, and by having the air entering the said short pipes through the perforations in their sides, the air and gas will be thoroughly mixed, and a more thorough combustion of the latter will take place with a greater generation of heat and less formation of soot or solid carbon than by having the air and gas mix interiorly of the pipes. The modified form of burner shown in Figs. 5 and 6 is therefore less preferable, and this form is only shown to illustrate that any other form of burner may be used with the air-ducts in the walls of the

furnace. This modified form shows the exterior pipe as formed with slots c^3 , having the short conical pipes c^5 extending from the interior pipe up into said slots, flush with the surface of the exterior pipe, and leaving annular or oblong spaces between the slots and the ends of said short pipes for the passage of the air. Perforations, however, are capable of being substituted for the spaces, if desired.

10 We do not make any claim for this construction, which is merely shown as another form of burner capable of being used with the air-ducts, as this form has already been patented.

Under the construction and arrangement of 15 the parts of the apparatus as shown the operation thereof will be as follows: The fire having been started in the heating chamber or furnace and the feed-pipes being sufficiently heated to decompose and convert the fuel 20 therein into gas, draft or suction is caused in the air-duct, and thereby the passing current of air becomes heated during its circuit of said duct, which extends around and near the inner surfaces of the walls of the chamber or furnace. The heated air is now passed into the 25 space or chamber within the exterior pipe of the burner, and in passing through the perforations of this pipe is mixed with the gas from the interior pipe, forming a blaze of intense heat.

30 This form of burner, in connection with the use of heated air, is especially adapted to blast-furnaces, owing to the steadiness and intensity of the flame produced thereby; also, it causes the flame to be projected to a greater extent than the ordinary burner, thereby not only greatly intensifying the heat in the furnace, but keeping the feed and gas pipes at the proper degree of temperature.

35 We do not restrict ourselves to the employment of a single burner constructed as described and supplied with heated air, as we contemplate the use of two or more such burners, according as circumstances may require;

40 nor do we confine ourselves to the employment thereof in connection with the particular number and arrangement of feed-pipes shown and described, nor to any other precise details, as minor changes may obviously be made with-

out departing from the principle of our invention.

We are aware that it is not broadly new to mingle heated air which is heated by the fire within the furnace with the gas in the burner for the purpose of increasing the combustion 55 of the gas, and thus intensifying the heat created, and we are also aware that it is not broadly new to construct burners in which the gas is passed out from an interior pipe surrounded by an air-pipe, the said pipes having common outlets for the gas and air, and we do not claim such a burner; but

50 What we do claim as new is—

1. The combination of a furnace-chamber provided with a hot-air duct in its walls surrounding the entire chamber and being heated therefrom, and having a suitable air-inlet, with a burner consisting of an exterior hot-air pipe connected at one end into said hot-air duct and formed with slots or apertures arranged 65 in a zigzag line in its upper side, an interior gas-pipe having registering apertures or slots 70 in its upper side and being arranged within said hot-air pipe, and short pipes connecting the registering apertures or slots in said gas 75 and hot-air pipes and having perforated sides, substantially as described.

2. A burner for gaseous fluids, comprising an exterior hot-air pipe formed with slots or apertures arranged in a zigzag line in its upper side, an interior gas-pipe formed with registering apertures or slots in its upper side and arranged within said hot-air pipe to form an air-chamber larger at the bottom than at the top, and short pipes connecting the apertures 80 or slots in said pipes, and having perforations 85 in their sides which form communication between the hot-air chamber and the gas-ducts formed by the short pipes, substantially as and for the purpose described.

90 In testimony whereof we affix our signatures in presence of two witnesses.

JOHN S. ANDREWS.
JAMES S. ROGERS.
